UNITED STATES PATENT OFFICE.

BURNS D. LOCKWOOD, OF INDIANAPOLIS, INDIANA.

PILOT FOR LOCOMOTIVES AND THE LIKE.

No. 890,077.

Specification of Letters Patent.

Patented June 9, 1903.

Application filed April 30, 1903. Serial No. 430,117.

To all whom it may concern:

Be it known that I, BURNS D. LOCKWOOD, a citizen of the United States, residing at Indianapolis, in the county of Marion and State of Indiana, have invented a new and useful Improvement in Pilots for Locomotives and the Like, of which the following is a specification.

My invention relates to the pilot of a steam locomotive, electric car, or other motor vehicle, and to means for attaching same to the end sill of the vehicle frame, the ordinary locomotive pilot consisting of a triangular wedge-shaped wooden frame-work having a top and bottom bar connected together by a series of inclined bars, and the whole secured to the end sill or buffer-beam by bolts.

My invention has for its object to simplify construction, and to provide a strong, rigid, compact, and durable metallic pilot firmly secured to the end sill without the use of the transverse top bar, and having its inclined bars adapted respectively, to interlock with, and to be removably fixed to the end sill.

The invention consists in features of novelty as hereinafter described and claimed, reference being had to the accompanying drawing forming part of this specification, whereon,

Figure 1, is a top plan view of my improved pilot applied to a locomotive end sill or buffer-beam, shown partly in horizontal section on line 1, 1, in Fig. 2; Fig. 2, a front elevation thereof; Fig. 3, a vertical transverse section through the pilot and end sill on line 3, 3, in Fig. 1; Fig. 4, a vertical transverse section to enlarged scale through the end sill and the upper part of the pilot on line 4, 4, in Fig. 1, showing the means for attaching the inclined bars thereof to the sill; Fig. 5, a horizontal section thereof on line 5, 5, in Fig. 4; Figs. 6, and 7, corresponding views to Figs. 1 and 2, showing a modification of the pilot; Fig. 8, a vertical transverse section to enlarged scale through the end sill and the pilot on line 8, 8, in Fig. 6, and Fig. 9, a horizontal section thereof on line 9, 9, in Fig. 8.

Like letters and numerals of reference denote like parts in all the figures.

Referring to Figs. 1, 2, 3, 4, and 5, a represents one form of my improved metallic pilot and b the end sill or buffer-beam to which the pilot a is fixed. The end sill b is preferably composed of cast steel integral throughout and may be of any suitable shape in cross

section and general configuration, such as shown, or otherwise, and adapted to the purpose of my invention as hereinafter particularly described.

The pilot a consists of a preferably flat bottom bar c composed preferably of rolled iron or steel (or cast steel) which in the assembled position of the parts is arranged horizontally flatwise at a suitable distance below and forward of the end sill b and similarly configured (or otherwise) in top plan to the corresponding base of the ordinary pilot.

Extending endwise between and adapted to connect the bottom bar c to the end sill b is a series of preferably circular bars d which are arranged side by side at a suitable distance apart and inclined upward and rearward from the bottom bar c to the end sill b according to the required contour of the pilot a.

Each inclined bar d is preferably flattened or formed at its lower end with a foot 1 which is adapted to bear on the bottom bar c and is fixed thereto by a rivet (bolt or screw) 2, the foot 1 being preferably, formed with a rear depending lug or heel 1' which is adapted to engage the inside edge of the bar c and thereby hold the bar d from forward displacement thereat and prevent shear stress on the rivet 2.

The upper end of each inclined bar d is preferably flattened or formed with an upright tongue, flange, or analogous member 3 having, preferably, oppositely beveled or dovetail side edges, and adapted to be inserted through the open end of and to fit closely within a correspondingly shaped pocket (recess or groove) 3' formed on (or in, or separately and attached to) the face of the front wall or other suitable corresponding member of the end sill or equivalent part of the frame to which the tongue 3 when so inserted is rigidly fixed by a rivet (bolt or screw) 4 passed through the tongue 3 and 3' in the said wall thereat as shown, the pocket 3' in the present case being closed at the bottom so as to form a support 5 for a shim 6 which is preferably, interposed (if required) between the support 5 and the tongue 3, whereby the latter with its corresponding bar d is vertically adjustable and the rivet (or bolt) 4 relieved from shear stress. Or if desired the tongues or members 3 and pockets 3', in lieu of being upright as described 110

may be horizontal and arranged on the underside of the end sill *b* as indicated by dotted lines in Fig. 4.

In assembling the pilot *a*, the bars *c* and *d* being first properly adjusted relatively to each other and fixed together by the rivets 2, the tongues or members 3 of the inclined bars *d* are simultaneously inserted within their respective pockets 3' and fixed to the end sill *b* by the rivets 4, the whole forming a strong, and durable pilot of greater rigidity and occupying less space than the cumbersome wooden pilot with little or no expense for repair; moreover if either of the inclined bars *d* becomes bent or broken, it can be removed and replaced without interfering with the other bars *d* or disconnecting the pilot.

In the modification of my improved pilot *a'* shown in Figs. 6, 7, 8, and 9, the inclined bars *d'* are preferably L-shaped in cross section and formed respectively, at their upper ends with an upright rectangular-shaped tongue 7 having a lateral flange 7' facially flush T-wise therewith, two or more of the bars *d'* at the middle portion of the pilot *a'* being connected together at a suitable distance from the tongues 7 by a cross bar 8 so as to form a suitable opening 9 thereat through the pilot *a'* for the coupler (not shown).

On (or in) the face of the front wall 10 of the end sill *b'* is formed a pocket or recess 10' which extends along the sill *b'* for the entire width of the pilot *a'* thereat (or the entire length of the sill *b'* as desired) the pocket 10' being open at the front and at one or both ends, and having along its front opening a top depending and a bottom upwardly projecting flange 11 adapted to engage the tongues 7 of the inclined bars *d'*, which in assembling the parts are inserted uprightly and side edgewise into and along the pocket 10' through either end thereof, the top and bottom portions of the tongues 7 being overlapped and held by the flanges 11, and on the proper adjustment of the bars *d'* relatively to each other, the outermost and a suitable number of the intermediate tongues 7 are secured to the end sill *b'* by rivets (or bolts) 12 which are passed through the lateral flanges 7' of the tongues 7 and the rear wall of the pocket 10' (or front wall 10 of the end sill *b'*) as shown, the other tongues 7 not so fas-

tened, being thereby held in place within the pocket 10'.

I do not limit myself to the particular shape described of the tongues or members 3, 7, 7', as they may be obviously otherwise configured and adapted to engage in correspondingly shaped receptacles therefor in the end sill or equivalent member of the locomotive or other motor vehicle frame for interlocking the inclined bars *d*, *d'*, therewith.

What I claim as my invention and desire to secure by Letters Patent is:

1. A metallic pilot for a locomotive, comprising a horizontal bottom bar and a series of inclined bars adapted respectively, to be fixed at one end to the horizontal bar and at the other end to interlock with the end sill of the locomotive, substantially as described.

2. A metallic pilot for a locomotive, comprising a horizontal bottom bar and a series of inclined bars adapted respectively, to be fixed at one end to the horizontal bar and at the other end to interlock with the end sill of the locomotive, and means for fixing the interlocking portions of the inclined bars to the end sill, substantially as described.

3. A metallic pilot for a locomotive, comprising a horizontal bottom bar and a series of inclined bars having respectively, at one end a foot adapted to bear on, and fixed to the horizontal bar, and at the other end a suitable member adapted to engage in a correspondingly shaped receptacle in the end sill of the locomotive, and means for fixing the said member to the end sill, substantially as described.

4. A metallic pilot for a locomotive, comprising a horizontal bottom bar and a series of inclined bars having respectively, at one end a foot adapted to bear on, and fixed to the horizontal bar, the said foot having a rear depending lug adapted to engage the corresponding edge of the horizontal bar, and means for fixing the inclined bars to the end sill of the locomotive, substantially as described.

In testimony whereof I have signed my name to this specification in the presence of two subscribing witnesses.

BURNS D. LOCKWOOD.
